CLAIM

The ornamental design for the implanting, sensing and reading device, as shown and described.

DESCRIPTION

FIG. 1 is a top plan view of an implanting, sensing and reading device;

FIG. 2 is a top plan view of an inserting unit of the implanting, sensing and reading device of FIG. 1;

FIG. 3 is a front elevation view of the inserting unit of the implanting, sensing and reading device of FIG. 2; and, FIG. 4 is a top plan view of a sensing and reading unit of the implanting, sensing and reading device of FIG. 1.

The broken lines throughout the figure views show portions of the implanting, sensing and reading device that form no part of the claimed design. The broken, breakaway lines in FIGS. 1, 2 and 4 also form no part of the claimed design, and anything between the breakaway lines forms no part of the claimed design.
